Primary Examiner — Celia Murphy*Assistant Examiner* — Clare Ann Gannon(74) *Attorney, Agent, or Firm* — Calfee, Halter & Griswold LLP(57) **CLAIM**

I claim the ornamental design for a folder, as shown and described.

DESCRIPTION

FIG. 1 is a front/right/bottom perspective view of a folder, shown with the front surface curled from upper right to lower left;

FIG. 2 is a front/right/bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a view of the folder in an open configuration. The dash-dot broken lines and the dashed lines at the right corners define the bounds of the claimed design. All other broken lines depict portions of the article that form no part of the claimed design.
